UNITED STATES PATENT OFFICE.

JAMES EDWARD SCHUMACHER, OF YORK, ENGLAND.

STEAM-ENGINE.

SPECIFICATION forming part of Letters Patent No. 601,385, dated March 29, 1898.

Application filed July 7, 1897. Serial No. 643,731. (No model.) Patented in England August 5, 1896, No. 17,280.

To all whom it may concern:

Be it known that I, JAMES EDWARD SCHUMACHER, a subject of the King of Prussia, Emperor of Germany, residing in the city and county of York, England, have invented new and useful Improvements in or Relating to Steam, Hydraulic, and other Engines, (for which an application has been filed in Great Britain, dated the 5th day of August, 1896, No. 17,280,) of which the following is a specification.

This invention relates to improvements in steam, hydraulic, and other engines—as, for example, such as are described and illustrated in the specification of United States of America Letters Patent No. 571,129, granted to me the 10th day of November, 1896, in which the supply of steam, water, compressed air, or other liquid or fluid is regulated or controlled by a circular valve having a continuous rotary motion imparted to it by suitable gearing—say, for example, from the fly-wheel shaft or other convenient moving part of the engine.

The objects of the present invention are, first, to adapt an engine controlled by a circular valve having a continuous rotary motion to be worked expansively; second, to arrange the circumferential grooves to be within the exhaust-jacket, whereby a much better flow, say, of steam is obtained, and consequently there is considerably less cylinder condensation; third, to reduce the friction on the face of the circular continuous-rotating valve, and, fourth, to provide means for reversing the engine.

The herein-described improvements may be applied to either horizontal or vertical engines.

In the drawings hereunto annexed this invention is shown applied to a horizontal engine adapted, say, for example, for use on a motor-car provided with two cylinders.

Figure 1 is a side elevation; Fig. 2, an end elevation; Fig. 3, a part sectional plan; Fig. 4, a sectional elevation on lines $x-x$, Figs. 3 and 5; Fig. 5, a part external elevation of the cylinders; Fig. 6, an enlarged part sectional elevation of the valve, its casing, and cut-off plates; Fig. 7, an enlarged part sectional plan of the valve-casing, showing one arrangement of cut-off plates with the valve removed; Fig.

8, a part sectional elevation of cut-off plates on line $w-w$, Fig. 7; Fig. 9, a plan of cut-off lever; Fig. 10, an enlarged sectional elevation for pressure-compensating arrangement for reducing the friction on the continuously-rotating circular valve; Fig. 11, an enlarged sectional elevation of the valve-seat, showing the arrangements of valve-ports and circumferential grooves; Fig. 12, an enlarged part sectional elevation of the valve-casing with the valve and cut-off plates shown in position; Fig. 13, an enlarged part sectional plan of the valve-casing and a plan of the valve; Fig. 14, a sectional elevation of a valve-seating, cover, cut-off plates, with valve shown in position and adapted to make, say, one rotation to, say, six complete revolutions of the crank-shaft; Fig. 15, a plan of valve-seating shown at Fig. 14 with valve removed; Fig. 16, a plan of under side of valve shown at Fig. 14; Fig. 17, a sectional elevation of a valve-seating, cover, cut-off plates, with a valve shown in position and adapted to make, say, one rotation to, say, three complete revolutions of the crank-shaft; Fig. 18, a plan of valve-seat shown at Fig. 17; Fig. 19, a plan of the under side of the valve shown at Fig. 17; Fig. 20, a sectional elevation showing arrangement of bosses for operating cut-off plates from the center.

Like parts in all the views are marked with the same letters and figures of reference.

In this invention one or more (preferably two, though not necessarily so) double-acting cylinders A and B are mounted and fixed upon a bed or framework (one or both) at a suitable distance from or opposite to each other.

In the drawings hereunto annexed the cylinders A and B are shown arranged parallel with each other, with the valve-casing (to be hereinafter described) arranged between them. Each of the cylinders is provided with two ports (marked, respectively, $A^2 A^4$ $B^1 B^3$) and with a piston (marked, respectively, D and E)—that is to say, piston D reciprocates in cylinder A and piston E reciprocates in cylinder B—capable of reciprocating therein by its connection with the fly-wheel shaft J by means of the piston-rods F and G and connecting-rods H and I and cranks K and K', slotted and weighted or otherwise.

The ports $A^2 A^4$ and $B^1 B^3$ in each cylinder

A and B are arranged at each end thereof, and they are respectively connected by suitable pipes or passages (marked L, M, N, and O) with a circular valve-casing P—namely, 5 port A² by passage L, port A⁴ by passage M, port B¹ by passage N, and port B³ by passage O—and both the cylinders are operated from a single valve S, rotating in the said valve-casing.

10 The valve-casing P is constructed as follows:

The casing P may be cast or built up in parts and may be of any suitable length, diameter, and thickness; but in this invention

15 it is preferred to build the seating up in parts and arrange one or more of the said parts to be capable of being turned or rotated within the other—that is to say, the part of the casing containing the circumferential grooves 20 (marked 1 2 3 4) and valve-ports (marked 5 6 7 8) are arranged so as to be capable of being turned or rotated within the portion of the casing P containing the exhaust jacket or ports, (marked 9.) The said parts are shown

25 retained in position by means of the circumferential lip q and flange q'. (Shown at Fig. 11.) The casing P is provided with a cover or mantle, hereinafter termed "covers" Q Q', at one or both ends, preferably at both ends.

30 In the center of the casing P is a hole R of suitable diameter and which extends the full length thereof—say in a vertical direction. Around this hole is arranged any required number of circumferential grooves 1, 2, 3, and 35 4—say, for example, four, as shown—that is, a circumferential groove is provided for each port. When the cylinders are placed directly opposite each other, the circumferential grooves in communication with the cylinders 40 may increase in size as they approach their respective cylinders. Otherwise they are of the same size all around. Each circumferential groove is in communication with a number—say, for example, three, or more or less,

45 if so desired—of, say, vertical holes or passages 5, 6, 7, and 8, hereinafter termed "valve-ports," having openings or orifices in or on the seating of the valve. For convenience of reference the odd figures of the cylinder-ports 50 and valve-ports are arranged to be in communication with each other, and in like manner the even numbers are in communication with each other—that is to say, circumferential groove 1 and valve-port 5 are in communication, circumferential groove 2 communicates with valve-port 6, circumferential groove 3 with valve-port 7, and circumferential groove 4 with valve-port 8.

55 In order that the arrangements of ports, circumferential grooves, and valve-ports may not be misunderstood, I will state again in a concise form the order of communication, namely:

60 For cylinder A port A², passage L, circumferential groove 2, and valve-ports 6 are in communication with each other. Port A⁴,

passage M, circumferential groove 4, and valve-ports 8 communicate with each other.

For cylinder B port B¹, passage N, circumferential groove 1, and valve-ports 5 are in communication with each other. Port B³, 70 passage O, circumferential groove 3, and valve-ports 7 are all in communication with each other.

75 Wholly or partially around, say, the valve-ports is formed the exhaust-jacket 9, which is employed for conveying away the exhaust through pipe 10, or when steam is employed it may, if so desired, but not necessarily so, be kept hot by live steam. The jacket is provided with an opening to the outer air, which may be the before-mentioned pipe 10.

80 On, say, the top of the valve-casing P is mounted and fixed the cover Q, having an opening 11, through which steam, water, or other liquid or fluid is admitted to valve-casing P. Within the said cover is the rotating valve S, which is provided with as many, (or more,) say, vertical openings s as there are valve-ports communicating with each circumferential groove. The valve S is mounted on a rod T, one portion of which passes, say, down or through the central hole R, while its upper portion passes through a gland T' in the cover Q. The upper end of the valve-rod 90 T is armed, say, with a bevel-wheel T², arranged to gear with a pinion J', mounted on the crank-shaft J. By this means a continuous rotary motion is imparted to the valve S. On the inner face of the valve S is also provided a number of apertures or recesses, preferably recesses s', for receiving the exhaust from the valve-ports and conducting it to the jacket 9. It will be noted that the admission-openings s pass entirely through the valve, while the recesses s' only pass partially through it. The surface of the valve-face between the apertures s and recesses s' is employed for closing the valve-ports not then in use.

95 In order to reduce the friction on the valve S as much as possible in a cover Q' to form what I term the "balance-cylinder," provided, say, at the bottom of the casing P is a piston U of rather smaller area than the valve. One portion—say the lower portion—of the rod V, upon which piston U is mounted, passes through a gland or hole in, say, the bed-plate C, while the upper part of this rod V (which does not revolve) may form a 100 step for the pendent portion of the valve-rod T, that passes through the central hole R; or the valve and piston may be connected together by any other convenient and equivalent means. The lower cover Q' is connected 105 to the steam, water, compressed air, or other fluid or liquid inlet 10, or to the cover Q by means of a pipe or passage X to enable, say, for example, the live steam to act upon the under side of the piston U at or about the 110 same or a slightly-reduced pressure as it acts upon the upper surface of the valve S, there-

by reducing the friction while preserving an equilibrium (or nearly so) of pressure. This portion of the invention may be used in combination with valve and its casing described in the specification of the before-mentioned Letters Patent.

When it is required to provide for a reversing action of the pistons D and E in the cylinders A and B, the portion of the casing P containing the valve-ports may be made to be capable of rotating therein, as shown at Fig. 11, when actuated by a hand or other lever Y or its equivalent, whereby the valve-ports 5, 6, 7, and 8 that in one position communicate, say, with the ports—say, for example, A² or B' at the top of the cylinder—may be altered to communicate with the bottom ports A⁴ or B³, or vice versa.

When the valve S and its casing Q are employed for compound engines, there will require to be a double circle of valve-ports 5 6 7 8 (see Figs. 14 to 16) provided between the exhaust-jacket 9 and the central hole R and a double set of openings s in the valve for communication therewith. This double set of valve-ports is in communication with each other and arranged to communicate with their respective circumferential grooves, as before described, so as to be capable for use for exhaust purposes.

By arranging the circumferential grooves to be within the exhaust-jacket a much better flow of steam can be obtained, and consequently a considerably less loss from cylinder condensation is the result. The valve is also kept at an even temperature by an outer casing or jacket when filled with either live steam from the boiler or by the exhaust-steam. Further, the cylinder condensation will be very little if any greater than in a jacketed cylinder with the ordinary slide-valve. Consequently the superiority of an engine fitted with this valve over an engine of the same size fitted with the ordinary valve is the less frictional resistance in driving the respective valves.

When it is required to work the engine expansively, cut-off plates Z Z' are employed and arranged to work one above the other in the cover Q between the face of the valve-seat P and face of the valve S, as shown at Fig. 6. The cut-off plates Z Z' are provided and perforated with a number of apertures or openings Z², corresponding with the number of valve-ports in the valve-seat P and openings in the exhaust-ring 9. The openings in the lower cut-off plate Z are smaller than those in the upper plate Z' owing to the former being provided with projecting lips Z³, arranged to pass into and work within the openings of the plate Z', as shown at Figs. 7 and 8. Any suitable arrangement of lever device may be employed for operating the cut-off plates—as, for example, the said plates may be provided with slots 12 and 13. A portion of each slot is concentric with the axis of the operating-lever 14 and the other

part so arranged as to form a cam for operating the plate. The cam-like portions of the two slots 12 and 13 are arranged in opposite directions, so that when pin 15 of the operating-lever 14 is actuating one plate it can travel in the concentric portion of the other slot. The cut-off lever 14 may be mounted upon a shaft 16, working in an axial bearing formed on the cover Q, or it may be attached thereto. When the lever is arranged as shown at Fig. 6, the pin 15 is mounted in a second lever 17, fixed to the shaft 16 near its lower end, or a separate lever 14 may be provided for each cut-off plate, as at Figs. 15 and 19. In this arrangement the ends of the lever 14 are notched to engage with cuneiform projections on the plates or to be worked from the center bosses 19 and 20 long enough to pass through the valve-seat, as shown at Fig. 20, being provided, respectively, on each plate Z Z' for this purpose for operating them from the center, as shown at Fig. 20.

The reversing-lever Y and cut-off lever or levers 14 are arranged, preferably, on the same side of the cylinder, so as to be easily within reach of the engine-man.

The action of the engine is as follows: From the drawings hereunto annexed it will be readily seen that, say, the steam is admitted to the cylinders A and B alternately above and below the pistons D and E, respectively, through the ports A² and A⁴ and B' and B³, the steam being conveyed thereto from casing Q through apertures s in the continuously-rotating valve S and the set of valve-ports in connection with the requisite circumferential groove. Thus, for example, say, if steam is admitted to port A² of cylinder A the steam enters the cover Q at 11 and passes through openings s, down valve-ports 6 into circumferential groove 2, and along passage L to port A². While the above operation is being performed, port A⁴ is open and would be used for the exhaust, which is conveyed through passage M to circumferential groove 4, valve-ports 8, and to recesses s', by which it is conveyed to the passage 9 and out through pipe or opening 10.

If the valve is constructed so as to make one rotation to six complete revolutions of the crank-shaft, as shown at Figs. 14 to 16, the inner portion of the valve containing the valve-ports and circumferential grooves will have to be moved, say, twenty degrees in one direction or forty degrees in the opposite direction, or thereabout, in addition to what lead may be required for reversing the engine. This arrangement of valve, instead of having three inlet and three outlet ports, as the valve shown at Figs. 17 to 19, and which makes one rotation to three complete revolutions of the crank-shaft, requires double the number of port-holes both as regards inlet and exhaust ports, and the seat of such valve is constructed with eight valve-ports instead of four or twelve—namely, two opposite to each other for each end of the cylinder and

connected to the same circumferential groove. It will therefore be understood that when steam is admitted by four ports in the seat of the valve the area of the inlet s is required to be large enough to supply one end of each cylinder, whereas if there are twelve valve-ports in the seat of the valve the inlets s in the valve are operating at one and the same time. Consequently they may be made considerably smaller than the area of the one just described, say about one-third of its area.

The following is an example of the working of the valve shown at Figs. 14 to 16 with the pistons D and E, as shown at Fig. 3.

15 Steam is admitted at B' in all cases (plus the lead) through valve-port 5 and is full on at three-sixteenths of the piston's stroke. When the piston E has traveled half of its stroke, steam is then admitted through valve-port 6 and port A² into cylinder A, the piston D having then completed its outward stroke. Both pistons now descend in their respective cylinders together until piston D has performed one-half of its stroke, when 25 piston E will then be at the end of its inward stroke and in position to be acted upon by steam through valve-port 7, entering cylinder B through port B³. The piston E then commences its return outward stroke. The piston D still continues its inward movement in cylinder A until the inner end of the said cylinder is reached. Then piston E will be again at its half-stroke in cylinder B. Steam being admitted through valve-port 8 to cylinder A through port A⁴ will then cause piston D to commence its return outward stroke.

When the engine is working expansively, and, say, the steam is quickly put on and is full on at three-sixteenths of the stroke, it 40 remains full on up to, say, one-half or one-third of the stroke and is cut off, say, when three-fourths of the stroke has been completed and engine works the remainder of the stroke expansively.

45 When the piston in cylinder A has completed, say, one-half of its stroke and the piston in cylinder B is at its highest or dead point, then steam may be admitted to the cylinder B; but in both cases the admission of steam is plus the lead, which varies according to circumstances.

The exhaust-port is preferably arranged, say, with or about one-eighth (of the stroke) lead and is so arranged that it is closed, say, 55 at or about the point when the piston has accomplished three-fourths or seven-eighths of its stroke. At Fig. 14 a double set of ports may be employed, as before described, for exhaust purposes to enable the steam to be 60 conveyed away when it is cut off at an early stage of the piston's stroke. The outer set of valve-ports is arranged to be in communication with the inner set, as shown.

Having now described the nature of my said invention, what I claim, and desire to secure 65 by Letters Patent, is—

1. In an engine the combination with a bed-plate, cylinders mounted on said bed-plate, a valve-casing arranged adjacent to said cylinders and communicating therewith, a valve-seat within the casing built up in parts as described and capable of being partially rotated for reversing purposes, circumferential grooves formed on the valve-seat, each groove communicating with a single port of one cylinder and with one or more openings in the face of the valve-seat, an exhaust-jacket as described surrounding the circumferential grooves, a hood covering the face of the valve-seat, a rotating valve mounted within the hood, perforations within the valve connecting the hood and circumferential grooves, recesses on the face of the valves connecting the circumferential grooves with the exhaust-jacket, cut-off plates perforated as described 85 and interposed between the valve-seat and face of the rotating valve, and the means described for operating them, substantially as set forth.

2. In an engine such as described, the combination of the outer casing perforated as described and arranged to form an exhaust-jacket, the valve-seat built up in parts as described fitted within said exhaust-jacket and arranged to be partially rotated for reversing 95 purposes, a number of circumferential grooves in the periphery of said valve-seat, valve-ports communicating with said circumferential grooves as described, an orifice in the center of the said valve-seat, a rotating valve 100 with a portion of its spindle passing down said central opening, means described for rotating said valve-cut-off plates perforated as described interposed between the valve-seat and the face of the valve, said cut-off plates 105 being armed with bosses passing into the central orifice a hood covering the rotating valve, a second hood at the opposite end of the valve-seat on which the valve rotates, a piston slightly smaller in area than the rotating 110 valve a short fixed rod mounted in said piston and arranged to form a step for the pendant portion of the rotating valve-spindle, and a pipe forming a communication between the upper and lower hoods of the valve-casing respectively above the rotating valve, and below the said piston, substantially as described and for the purposes set forth.

In testimony whereof I have hereunto signed my name to this specification in presence of two subscribing witnesses.

JAMES EDWARD SCHUMACHER.
